UNITED STATES PATENT OFFICE

HARVEY WILLIAMS, OF MASSILLON, OHIO, AND JOSEPH W. MCHUGH, OF PITTSBURGH, PENNSYLVANIA, ASSIGNEES TO PITTSBURGH STEEL FOUNDRY CORPORATION, OF GLASSPORT, PENNSYLVANIA, A CORPORATION OF PENNSYLVANIA

ANNEALING BOX

Application filed February 10, 1928. Serial No. 253,364.

The invention relates to annealing boxes of the type in which a hood rests upon a flat-surfaced base of rectangular form and of very heavy section provided with a peripherally disposed uprising flange which, with the lower edge of the hood, forms a trough in which sand is packed to prevent ingress of air during the annealing operation. These boxes are subjected to very high temperatures, and the corners of the base plate, being heavy and unsupported, sag sufficiently under the heating to break the sand seal, permitting air to reach the hot materials inside of the hood. This sagging of the corners not only breaks the sand seal, but drags on the floor when taking the box out of an oven.

The object of the invention is to provide a base for such an annealing box in which the tendency of the corners to sag is substantially eliminated, and which requires less metal in its construction than prior bases.

The invention resides in the provision of an annealing box base plate having its corners of reduced section for decreasing the weight of unsupported metal at those points and thus substantially eliminate sagging and consequent ingress of air during the heating. Preferably this is accomplished by providing a base having corners biased from the normally substantially rectangular outline of the base.

In the accompanying drawings, which illustrate the preferred embodiment of the invention, Fig. 1 is a plan view of the improved base with a hood set thereon; Fig. 2 a longitudinal sectional view taken on line II-II, Fig. 1; Fig. 3 a transverse sectional view taken on line III-III, Fig. 1, the hood not being shown in Figs. 2 and 3 for simplicity of representation; and Fig. 4 a detail sectional view taken on the line IV-IV, Fig. 1.

Referring to these figures, the structure shown comprises a material-supporting base 1 of fundamentally rectangular outline, provided peripherally with a vertical flange 2. On its under side parallel grooved roller tracks 3 and 4 are provided, together with spaced reinforcing webs or ribs 5, and at its ends there are coupling lugs 6 for attachment to a means of moving the box. A cover or hood 7, of the substantially rectangular form

commonly used, rests on the upper surface of the base 1 inside the flange 2, the space between the hood and the flange being filled with a packing material, such as sand, to seal the interior of the hood against the ingress of air during an annealing operation.

The base is fundamentally rectangular, but according to the invention its corners are biased in a manner similar to that shown in Fig. 1. This biasing or cutting back of the corners is carried inwardly to bring the surfaces of the flange on the biased corner as near to the corners of the hood as is consistent with adequate sealing.

In the use of annealing boxes and hoods the sides and ends of the latter generally buckle considerably, so that provision is made for a trough between the hood and the base flange which is wide enough to allow such distortion without consequent breaking of the seal. The meeting of the sides and ends, however, has a reinforcing effect upon the corners, so that they do not buckle appreciably, and for this reason the biased corners may be cut back to form a narrower trough than is used at the sides and ends.

The effect of this cutting off the corners is to materially decrease the amount of unsupported metal at those points, so that there is little, if any, tendency for the corners to sag under heat, and a perfect seal can be maintained during the annealing operation. The corners may be biased to truncate the corner angle to form a single plane connecting the two adjacent sides; or they may be arcuate. The somewhat arcuate corner 8 shown in Fig. 1 is preferred because when thus biased the corner is brought closer to the hood than by making it truncate as defined above, and the unsupported metal at the corner is thus reduced to a minimum.

In order to further reduce the weight at the corners of the base, the thickness of the corner section may be reduced, as shown in Fig. 4, where the section of the bottom 1 at the corner decreases outwardly, being a minimum at the outermost corner.

By the use of this form of annealing box base, all danger of distortion sufficient to disturb the seal is eliminated. The base can

100

be made as easily as the forms hitherto used, and because less metal is required, the bases are cheaper, are easier to move, and less heat is required in bringing the box and its contents up to annealing temperature.

5 According to the provisions of the patent statutes, we have explained the principle and operation of our invention, and have illustrated and described what we now consider to be its best embodiment. However, we desire 10 to have it understood that, within the scope of the appended claims, the invention may be practiced otherwise than as specifically illustrated and described.

15 We claim:

1. An annealing box comprising a bottom of substantially rectangular outline provided at its edges with a peripheral upwardly extending flange, and a hood adapted to rest on said bottom and to form with said flange a trough for a sealing medium, the corners of said bottom being biased to bring said flange closer to the hood at the corners than along the sides and thus to reduce the amount of 20 unsupported metal at the corners and to eliminate the breaking of a seal by the sagging of corners when the box is in service.

2. An annealing box comprising a base of substantially rectangular outline provided at its edges with a peripheral upwardly extending flange, and a hood adapted to rest on said base and to form with said flange a trough for a sealing medium, the corners of the base being reduced in section outwardly from adjacent 25 the corners of the hood to eliminate breaking of a seal by the sagging of corners when the box is in service.

3. An annealing box comprising a base of substantially rectangular outline provided at its edges with a peripheral upwardly extending flange, and a hood adapted to rest on said base and to form with said flange a trough for a sealing medium, the corners of said base being biased to bring said flange closer to the corners of the hood than at the sides and being also of reduced section outwardly from adjacent the corners of the hood to reduce the amount of unsupported metal at the corners and to eliminate the breaking of 30 a seal by the sagging of corners when the box is in service.

In testimony whereof, we hereunto sign our names.

HARVEY WILLIAMS.
JOSEPH W. McHUGH.
